PRESSURE RELIEF VALVE

Philip W. Embury, Jr., Fairport, N.Y., assignor to
Qualitrol Corporation, Fairport, N.Y.

Filed Feb. 8, 1971, Ser. No. 113,803

Term of patent 14 years

Int. Cl. D23—01

U.S. Cl. D23—19

FIG. 1

FIG. 3

FIG. 2

FIG. 1 is a perspective view of a pressure relief valve embodying my new design showing the front, top and one side thereof;

FIG. 2 is a perspective view showing the back, the bottom and the opposite side thereof; and

FIG. 3 is a bottom plan view thereof, with the ring omitted for convenience of illustration.

I claim:

The ornamental design for a pressure relief valve, as
